DESIGN FOR A DRESS

Charlotte Marie Neuhardt, New York, N. Y.

Application April 23, 1940, Serial No. 91,880

Term of patent 3½ years

To all whom it may concern:

Be it known that I, Charlotte Marie Neuhardt, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design.

Fig. 2 is a rear view thereof, and

Fig. 3 is an enlarged fragmentary view of the

dress shown in Fig. 1 illustrating the belt member in detail.

The characteristic feature of my design resides in the combination on the collarless dress disclosed of the specific belt member having a stitched tie and gathered elastic bands extending from the pointed ends in association with the embroidered pocket as shown.

I claim:

The ornamental design for a dress, substantially as shown and described.

CHARLOTTE MARIE NEUHARDT.
